UNITED STATES PATENT OFFICE

D GEORGE DANNER AND JOSEPH GLENN THOMPSON, OF MINEBURN, IOWA; SAID THOMPSON ASSIGNOR TO SAID D GEORGE DANNER

PLUNGER DEVICE FOR DISPLAYING MERCHANDISE

Application filed September 6, 1927. Serial No. 217,715.

The object of our invention is to provide a plunger device for displaying merchandise.

It is a common practice to provide display cartons for cookies, crackers, biscuits and the like. These are usually placed on an inclined shelf or the like, so that the upper or display end of the carton is conveniently visible and also conveniently accessible. Cookies, crackers or other merchandise are taken from the top of the container.

The object of our device is to provide a plunger in the container readily adjustable for moving the contents, so that the contents will always be near the top of the container.

With these and other objects in view, our invention consists in the construction, arrangement and combination of the various parts of our device, whereby the objects contemplated are attained, as hereinafter more fully set forth, pointed out in our claims, and illustrated in the accompanying drawings, in which:

Figure 1 is a rear elevation of a battery of devices embodying our invention.

Figure 2 is a vertical, detail, sectional view taken on the line 2—2 of Figure 1.

Figure 3 is a perspective view of the plunger; and

Figure 4 is a detail, sectional view of the plunger actuating rod.

In the accompanying drawings, we have used the reference numeral 10 to indicate generally the legs of a supporting shelf or display rack, having the shelf members 12 and 14, which are connected at their lower edges and are inclined respectively forwardly and upwardly and upwardly and rearwardly, as perhaps best shown in Figure 2.

It is the practice to set display cartons 16 on these shelves, with their vertical axes inclined upwardly and forwardly as shown in Figure 2.

The carton 16 may be provided with a removable transparent cover member 18.

The merchandise is sometimes put into the carton in bulk, and sometimes as in the case of fancy cookies and cakes, is carefully laid in and the individual pieces are kept apart by fillers and separator strips.

In the case of our improved device, the

carton 16 is provided in its bottom with a hole 20. Resting against the bottom of the carton is a plunger 22. The hole 20 is located a little below the center of the bottom of the carton, considering the carton in the position shown in Figure 2.

The plunger 22 is preferably provided with some means for connecting with the plunger actuating rod. In the present instance, we have shown the plunger 22 provided with a projecting socket 24, which when the plunger is in the bottom of the carton extends into the hole 20.

Any suitable plunger actuating means may be provided.

We have shown in our drawings a novel form for such a device. Mounted on the rear or underside of the shelf 14 is a flange 26, which may be secured to the shelf member 14 by means of screws 28. Projecting from the flange 26 is a tubular bearing and guide member 30. The shelf member 14 has a hole 50 registering with the tubular bearing 30.

A plunger rod 32 is slidably mounted in the bearing member 30 and projects through the flange 26 and is adapted to have its inner end received in the socket 24.

The plunger rod 32 may be locked in the bearing 30 at different points of adjustment by means of a set screw 34. At its outer end, the rod 32 has a reduced portion 36 on which a sleeve 38 may be mounted.

At the outer or lower end of the sleeve 38, a detachable handle 40, provided with a reduced end 42, may be used. The reduced end 42 is snugly received in the end of the sleeve 38. The sleeve 38 and bearing 30 may be connected by a flexible member, such as a small chain 34.

The sleeve 38 is used for affording an extension of the rod 32, so that the rod 32 may be used with cartons of different depths.

The handle 40 may be employed with a series of plunger rods.

In actual practice, our improved plunger display device is operated as follows:

It is the experience of merchants that where merchandise is displayed in cartons like the carton 16, customers will purchase from the cartons which are full. It is harder

to sell from cartons which are partially empty.

We have found by actual tests that where our plunger display device is used, customers will buy much more freely than from cartons which have been partially emptied.

Where our device is employed, the plunger 22 is normally at the bottom of the carton.

In the particular carton here shown, we 10 have shown the separator strips 46 and the filler sheets 48 for keeping the merchandise pieces 50 separated.

After the top layer or two of the merchandise has been sold, the user of a device of this 15 kind fits the handle 40 to the sleeve 38 and shoves the plunger rod 22 upwardly, thus advancing the plunger rod 22 upwardly and bringing the remaining top layer of goods to the upper end of the carton.

20 As the goods are successively removed from the top layers, the succeeding layers are moved toward the top of the carton, so that the carton appears to be full, and so that the goods are near the top.

25 Goods so displayed are sold more easily and rapidly than goods which appear to be half way down toward the bottom of the carton.

It will, of course, be understood that some 30 changes may be made in the arrangement and construction of the parts of our improved device without departing from the real spirit and purpose of our invention, and it is our intention to cover by our claims any modified 35 forms of structure or use of mechanical equivalents, which may be reasonably included within their scope.

We claim as our invention:

1. In a device of the class disclosed, a pair 40 of side members, a V-shaped trough between them for receiving a carton, a bearing sleeve mounted on one of the walls of said trough, a rod mounted in said sleeve and adapted to coact with the contents of a carton received 45 in said trough and a detachable extension for said rod whereby the effective length of said rod may be increased without the rod projecting out of the bearing sleeve to a prohibitive degree when the carton is in filled 50 condition.

2. In a device of the class described, a pair of side members, a V-shaped trough between them for receiving a carton, a bearing sleeve, a rod mounted in said sleeve carried by said 55 trough and adapted to coact with the contents of a carton received in said trough, a detachable extension for said rod and means carried by said sleeve for locking said rod in various positions of its adjustment relative 60 thereto, said last means coacting with said extension when it assumes a position within said bearing.

Des Moines, Iowa, September 1, 1927.

65 D GEORGE DANNER.
JOSEPH GLENN THOMPSON.
